UNITED STATES PATENT OFFICE

2,565,789

WELL CASING GUN PERFORATOR

James O. Tow, Huntington Park, Calif., assignor
to McCullough Tool Company, Los Angeles,
Calif., a corporation of Nevada

Application August 23, 1947, Serial No. 770,232

2 Claims. (Cl. 164—0.5)

1

This invention relates to guns of the type employed for perforating casing in wells by shooting projectiles therethrough, and relates in particular to a perforating gun having a separate magazine for powder charges.

It is an object of the invention to provide a perforating gun having a body equipped with radially extending barrels to receive projectiles, and having a chamber communicating with the inner ends of these barrels, which chamber is adapted to receive a magazine which carries the powder charges for propelling the projectiles from the barrels when the gun is fired. A feature of the invention is that the arrangement of cooperating parts contributes to safety in handling of the gun for the reason that the powder chambers of the magazine may be loaded and kept separate from the gun body which has the projectiles therein, until such time as assembly of the gun is required so that it may be in condition for lowering into the well.

It is a further object of the invention to provide a well casing perforating gun having a body with barrels to carry the projectiles and an insertable magazine which carries all of the powder charges required for the firing of the gun. The powder charges for propelling the projectiles may be fired by any of the known electrically or mechanically actuated firing means, but in the simple form of the invention shown herein the propellant charges are fired through use of ignition passages which may be arranged to carry the ignition effect, such as flame and pressure, to the powder chambers of the magazine.

It is an object of the invention to provide a perforating gun comprising a body and a replaceable magazine which, due to its relative simplicity, may be replaced at small cost compared to the total value of the perforating gun.

Further objects and advantages of the invention may be brought out in the following part of the specification, wherein details of several forms of the invention are described for the purpose of fully disclosing the principles of the invention without limiting the scope thereof set forth in the appended claims.

Referring to the drawing which is for illustrative purposes only,

Fig. 1 is a sectional view showing a preferred embodiment of the invention.

Fig. 2 is a cross section taken as indicated by the line 2—2 of Fig. 1.

Fig. 3 is a fragmentary cross section showing an alternative arrangement wherein the inner

2

ends of the projectiles extend into the powder chambers.

Fig. 4 is a cross section showing a form of the invention wherein the ignition passages are formed in part by spaces provided between the internal wall of the gun body and the external wall of the magazine.

Fig. 5 is a fragmentary sectional view taken as indicated by the line 5—5 of Fig. 4.

10 In the form of the invention shown in Figs. 1 and 2, the perforating gun is provided with a cylindric axially elongated body 10 having an axial bore 11 defining in the body 10 an axially elongated space referred to herein as the magazine chamber 12. The lower end of the bore 11 may be permanently closed if desired, as by means of a screw plug 13, and the upper end of the bore 11 may be left open, this upper end of the bore 11 being covered when the perforating gun is assembled by a screw cap 14. The cap 14 is provided with a rope socket 15, by which the perforating gun may be connected to the lower end of an electrified cable 16 of the type normally employed for lowering electrically operated devices into wells, such cables 16 having at least one internal insulated conductor within its outer cable sheath.

15 The body 10 has a plurality of radial bores forming radial barrels 17 to receive projectiles 18. A magazine 19 comprising a cylindric metal bar is disposed in the magazine chamber 12 of the body 10. The external diameter of the magazine 19 is slightly less than the internal diameter of the body 10, so that the magazine 19 may be slid in and out of the chamber 12. The magazine 19 is oriented within the chamber 12 by aligning means consisting of an interengagement between the upper portion of the body 10 and the upper portion of the magazine 19. The aligning means is shown as a keyway 20 in the upper portion of the body 10 adapted to be engaged by a pin 21, which projects from the upper portion of the magazine 19. The magazine 19 has therein a plurality of powder chambers 22 in cooperative relation to the barrels 17. These powder chambers 22 are formed by openings 23 drilled in the magazine 19 in axial alignment with the respective barrels 17. The openings 23, however, do not extend entirely through the magazine 19 from side to side thereof, but a thin wall 24 is left at the front end of each opening 23 to confront the rear end of a projectile 18. After propellant charges 25 are placed in the powder chambers 22, the rear ends of the powder chambers are closed by plugs 26 which may be formed

from rubber compound, and as shown at 28a, metal discs may be placed at the rear ends of the plugs 26.

At the upper end of the magazine 19 there is a recess 27 defining at its lower end a priming charge chamber 28 to receive a priming charge 29 of powder ignitable by an electrically actuated fuse 30 carried in the lower end of a plug or fuse holder 31 which enters the upper part of the recess 27 when the gun body 10 is screwed into the cap 14. From the cable 16, an electrical conductor 32 is carried through the fuse holder 31 to the fuse 30 which, in accordance with accepted practice, may be grounded with the cap 14, which is in turn grounded with the sheath of the cable 16. From the priming charge chamber 28, an ignition passage 33, of small diameter, is extended within the magazine 19 to the uppermost powder chamber 22 and small diameter ignition passages 34 connect the powder chambers 22 in series so that when, by electrical energization, the fuse 30 is caused to ignite the priming charge 29, the ignition effect from the firing of the priming charge 29, such ignition effect consisting of flame and/or pressure, is carried downward through the ignition passages 33 and 34 and through the powder charge chambers 22 to ignite the propellant charges 25 therein. When the pressures in the powder charge chambers 22 develop to a value sufficient to shear the walls 24, which pressures develop substantially instantaneously, the walls 24 and the projectiles 18 which rest against the same, are propelled outwardly from the barrels 17 at high velocity to perforate and penetrate the walls of the well, including the casing which may be set therein.

In the alternative form of the invention shown in Fig. 3, I show parts bearing similarity to parts previously described. Accordingly, these parts will be indicated by numerals previously employed having the suffix *a* applied thereto. The gun body 10a of Fig. 3 has radial barrels 17a to receive projectiles 18a, the inner ends of which project into the forward ends of powder chambers 22a formed in a magazine 19a which is received in the axial chamber 12a of the body 10a. The rear ends of the powder chambers 22a are closed by walls 36 integral with the magazine 19a and displaceable walls are formed in the forward portions of the powder chambers by cups 24a insertable in the front end portions of the powder chambers 22a after propellant charges 25a are placed therein. The barrels 17a may be sealed by use of rubber plugs 38.

The uppermost powder chamber 22a, Fig. 3, is arranged to receive ignition products from the firing of a priming charge through an ignition passage 33a, and the chambers 22a are connected by ignition passages 34a arranged so that the upper or forward ends thereof communicate with the chambers 22a adjacent the side walls of the cups 24a, so that the cups act as means for delaying the transmission of the ignition effect from each of the chambers 22a to the succeeding chamber 22a. Before the ignition effect, such as flame and/or pressure, can pass into the upper end of a passage 34a, the cup 24a and the projectiles 18a seated therein must be displaced outwardly. In this manner, a sequential firing 70 of the propellant charges 25a is accomplished.

In the form of the invention shown in Figs. 4 and 5, the arrangement and cooperation of parts is the same as that as shown and described with relation to Fig. 3, with the exception 75

that the ignition passages which connect the powder charge chambers 22a are formed partly externally of the magazine 19a by elongated spaces which exist between the inner surface of the body 10a and the external surface of the magazine 19a. As shown in Fig. 5, an upper ignition passage 33a is provided through which the ignition flame or pressure is carried to the uppermost powder chamber 22a to ignite the propellant charge 25a therein. A radial ignition passage section 40 connects the uppermost powder chamber 22a with a groove 41 cut in the external surface of the magazine 19a. The lower end of the groove 41 communicates with the next downwardly succeeding powder charge chamber 22a through a radial passage 42. The ignition passage 40, the groove 41, and the passage 42 form a series passage connection between the two uppermost powder chambers 22a through which the ignition flame and/or pressure may pass. By the use of similar radial holes or passages 40a and 42a and interconnecting grooves 41a, the powder charge chambers 22a arranged in the magazine 19a below the uppermost chamber 22a, are interconnected in series.

I claim as my invention:

1. In a perforating gun of the character described, the combination of: a body having an axial chamber with an opening at least at one end thereof, said body having a radial barrel to receive a projectile; a magazine arranged to be entered into said chamber through said opening thereof, said magazine having a powder chamber operatively aligned with said barrel for receiving a propellant charge for propelling the projectile, and an ignition passage communicating with said powder chamber, the internal wall of said body and the external wall of said magazine being cooperatively formed so as to produce an extension of said ignition passage; a displaceable wall disposed between the projectile and the propellant charge; and means operative to apply an ignition effect to said extension so that it will be carried through said ignition passage to fire said propellant charge.

2. In a perforating gun of the character described, the combination of: a body having an axial chamber with an opening at least at one end thereof, said body having a radial barrel to receive a projectile; a magazine arranged to be entered into said chamber through said opening thereof, said magazine having a powder chamber operatively aligned with said barrel for receiving a propellant charge for propelling the projectile, and an ignition passage communicating with said powder chamber, the internal wall of said body and the external wall of said magazine being cooperatively formed so as to produce an extension of said ignition passage; and means operative to apply an ignition effect to said extension so that it will be carried through said ignition passage to fire said propellant charge.
